SAUSAGE LINKING MACHINE

James J. Prohaska, Chicago, Ill., assignor to Industrial Patents Corporation, Chicago, Ill., a corporation of Delaware

Application September 18, 1943, Serial No. 502,948

11 Claims. (Cl. 17—34)

1

This invention relates to an improvement in a machine for linking a stuffed sausage casing and more particularly to that type of machine wherein a string is tied around the outside of a stuffed casing to form the individual links.

It is an object of this invention to provide an improved machine for tying a stuffed casing to form links.

It is another object of this invention to provide an improved means for severing the string wrapped around the casing.

Another object of this invention is to provide a positive shearing means for severing the string after the tying operation is complete.

Another object is to provide an improved knife and shearing edge construction for a string tying and linking machine.

Other objects will become apparent from the specification below.

In the drawings:

Figure 1 is an assembly view, in perspective, of the type of machine to which the present invention is particularly adapted.

Figure 2 is a perspective view of the first tying station looking from the inlet end of the machine shown in Figure 1, with the present improvement shown in position adjacent the tying ring and with the string carrying tying ring in position just after the start of a tying cycle.

Figures 3 to 8 show a side elevation of the tying station of Figure 2 with the string carrying ring and the string depicted in certain characteristic and different positions through which they pass in completing the tying cycle.

Figure 9 is a plan view partly broken away showing the carrying ring, the anvil, and knife with a string laid on the shearing edge.

Figure 10 is a side elevation partly broken away showing the resilient mounting of the knife blade on its carrying arm.

In the sausage making art, it has been the practice in the past to link stuffed sausage casings by pinching a length of the stuffed casing off with the fingers and manually twirling the portion of the casing disposed between the fingers. This twirling motion causes the casing to be twisted at the points where it is pinched by the fingers and linking is thus accomplished. This operation is repeated at spaced points to complete the linking of the entire casing.

Recently machines have been proposed for accomplishing the linking of stuffed casings and, in certain of these machines, a string is tightly wrapped around a casing to pinch the casing down to form the individual links. One form,

2

which such a mechanism may take, is shown in the patents to Demarest et al., No. 2,228,075, January 7, 1941, and No. 2,258,644, October 14, 1944. This machine has been found to operate successfully, however, some difficulties have been encountered in using these machines when they are provided with cutting means for severing the string such as are shown in the mentioned patents.

10 As taught by Demarest, the string is severed after being wrapped around a casing by holding the string taut while a sharp edge is driven against the tensioned string. The machine is operative to stretch the tied string taut between the casing and the tying means after the string has been wrapped around the casing, and the cutting means is then driven against the tensioned string. It has been found that unless the knife used for cutting the stretched string is kept quite sharp, 15 the severing will not be completed as intended and also, if the string is not tensioned properly, then faulty cutting results.

Whenever the string is not properly severed, the machine becomes jammed and much time is lost in clearing it in order to again set in motion a proper tying cycle.

The present invention has been made to provide means to effect a more expeditious severing action, and it teaches the use of means for positively shearing the string, which means include a self-sharpening knife. The mechanism of this invention is operative to sever the string regardless of the tension with which it is drawn after the completion of the tying operation and, thus, all of the defects of the prior art devices are eliminated.

As stated above, the tying linking method causes a string to be passed around a casing a plurality of times while it is drawn tight. The shearing means of the herein disclosed improvement comprises a fixed and movable means, the fixed shearing edge being placed in the normal path the string follows in being wrapped around the casing, while the movable edge is adapted to be driven across the fixed edge at timed intervals in the tying cycle to sever the string. Means are also associated with the fixed edge to direct the string around one end of the fixed edge during the wrapping cycle, but are operative to draw the string across the fixed edge just as the knife is driven through its cutting stroke.

Referring more particularly to the drawings, the combination of the elements forming the machine to which the present invention is adapted, is seen in Figure 1. In this machine, the stuffed casings are fed from the left hand side of the

machine through the tying stations to the outlet on the right hand end and the stuffed casing 10 is initially presented to the infeed conveyor belts 11 for delivery through the machine. The stuffed casing is delivered from the conveyor 11 through the two tying stations 12 and 13, and passes from these stations to the outlet conveyor belt 14. The feed through the machine is intermittent and the stuffed casing is stopped at the two tying stations, after a predetermined length of casing has been driven through the machine, so that while the casing remains stationary the tying means may be driven to link the casing. Each of the tying stations wraps a string around the casing and each string is then severed, whereupon the feed means becomes energized to carry the casing forwardly a predetermined distance to present the following portion of the casing to the tying means.

The tying means itself is best shown in Figure 2 and basically it includes a rotating ring 15 which is adapted to be driven around the casing while it is held stationary, in a generally concentric relation, within the ring. The string 16 for tying the casing is delivered through suitable guiding and tensioning means and the free end of the string is engaged on the side wall of the rotating ring 15, by hooks 17 and 18. The hooks are driven to engage the string by cam means operated in timed relation to the movement of the casing through the tying station so that the string is clamped on the ring to be carried around the casing in a sequence which will be more fully described below.

When the string is engaged by hooks 17 and 18 and the ring 15 is rotated, the string is carried around the casing. Means are provided to cooperate with the ring to measure off a required length of string and when a proper length has been pulled through the delivery means, the tying is completed by driving the ring around the casing a plurality of times. Simultaneously with the wrapping of the string around the casing, the string is pulled back by the delivery means to tension it in a manner to draw the casing in so as to form the separation between the individual links.

After the string has been carried around the casing and drawn in to provide the ends of each link, the end of the string is released from hooks 17 and 18 and these hooks continue on their way to engage the string between the casing and the string delivery means. When the hooks again engage the string the ring is driven to draw the string down from the casing and hold it taut while a knife 19 is driven into engagement with the stretched string to sever it.

So much of the machine as has already been described is conventional structure and the present improvement resides in presenting a shearing edge against which the string is engaged at each of the tying stations so that the knife may be reciprocated against the edge to effect a severance thereof.

The means for accomplishing this placement of the string on a shearing edge for cooperation with the knife is best seen in the plan view of anvil 29 (Figure 9) wherein the string is shown laid upon shearing edge 30 during one phase of the tying operation. It is there seen that the shearing edge 30 is positioned to cooperate with the cutting edge of knife 19 so that the string is positively engaged between shearing means whereby it is severed. The fixed shearing edge 30 is normally disposed to extend somewhat into

the space between the inner surface of the ring and the stuffed casing passing through the ring (see Figure 2), so that when the string is drawn taut between the casing and hook 17, upon completion of the tying operation, as shown in Figure 8, the shearing edge 30 will be projected across the path the string normally follows in being wrapped around the casing to insure that proper shearing will always take place.

Anvil 29, upon which the shearing edge 30 is formed, is fixedly supported from the base plate 31 of the machine, and it is necessary, during the wrapping of the string around the casing, to provide means for directing the string around one end of the fixed shearing edge which, as stated above, projects across the normal path the string would follow in being wound around the casing. Thus, referring again to Figure 9, cam surface 32 is shown which is preferably formed integral on the anvil, against which the string is engaged as it is carried around by the ring during the tying operation. The string passes over the cam surface 32 to be deflected from its normal path and then it falls onto the shearing surface 30, as the hooks 17 and 18 carry the free end of the string around the lower half of the ring's travel. As the hooks pass upwardly and over the top of the casing, the string is first drawn taut and then it slides off of the sloping cam surface 32 and the shearing edge 30, to be drawn tight around the casing.

When the winding operation has been completed, and the free end of the string has been released, the thread hook 17 and gripper hook 18 will be projected to engage the string passing from the casing to the supply. Continued movement of ring 15 will carry this portion of the string forwardly until the string engages the cam surface 32 and moves up onto shearing edge 30. The motion of the ring is then terminated and the knife may be reciprocated inwardly to shear the string to complete the tying cycle.

Integral on anvil 29 and spaced from the side wall of ring 15, is a forwardly projecting nosepiece 33 which is adapted to engage and guide the string when it is released from the measuring means, as shown in Figure 4. When the string is slack at this point in the cycle, it might possibly loop itself completely over the anvil so that the tying operation would be interrupted. Nosepiece 33 has been provided, to prevent this from happening.

The nosepiece 33 is also inclined downwardly at an angle from the anvil 29 as is best shown in Figures 3 to 8 so that as the knife is reciprocated inwardly, it will first engage the nosepiece 33. The knife is lifted by the inclined surface of nose 33, against the tension of a spring through which the knife is fixed to its carrying arm and a tight and exact cooperation between the anvil and knife-edge thus results. The bearing of the knife on the nosepiece guides the knife edge into exact alignment with the shearing edge 30 and positive cutting of the thread is accomplished. It is to be noted that the knife in passing over the nose 33 and the shearing edge 30 engages each of these surfaces tightly, and a self-sharpening action takes place.

In the preferred form, the knife-edge is provided with an angularly ground cutting edge 34 inclined in a manner to trap the string between the tip 35 of the knife-edge and the shearing edge 30 whereby the string cannot escape from between these two elements during the cutting. As the knife moves forwardly, the string is thrown

into the corner 36 formed on anvil 29 between the fixed edge 30 and nose 33, and as the knife-edge 34 passes over the shearing edge 30, the string is sheared.

When the linking machine shown in the Demarest et al., patent is being operated with the present invention applied to it, the casing is intermittently delivered through the tying stations by the conveying means 11 and 14. After the casing has been delivered a fixed distance through the machine, it is held stationary within the ring tying stations 12 and 13 in concentric relation with respect to the tying rings 15, while the free end of the string which is engaged in clamps 17 and 18, as shown in Figure 2, is carried around the casing as the ring is driven. During rotation of ring 15, the sequence of events shown in Figures 3 through 8 takes place.

As the casing comes to rest within the string carrying ring 15 of the tying station, the ring begins to rotate and the free end is carried upwardly from the position shown in Figure 2 to the position shown in Figure 3, and a measured amount of string is drawn from the supply by drawing the string around the pin 40 slidably mounted in ring 15. When the proper length of string has been drawn out, cam means engage the end of an arm carrying pin 40 to drive the pin in flush with the face of the string carrying ring and at this point of the tying cycle (Figure 4), the string is rather loosely disposed between the string supply including the hold-down arm 41 and the clamping means 17 and 18 carried by the ring.

When the string has been carried around by the ring to the further position shown in Figure 5, the string is snugly disposed around the periphery of the casing. As the ring continues its rotation around the fixed casing, the string is drawn tightly into the casing and simultaneously, the hold-down arm 41 is driven upwardly so that the string is pulled tight between clamps 17 and 18 and the guide 42 (Figure 5), to draw the casing inwardly to define the end of a link. As the ring continues to rotate and the hold-down arm to lift, the casing is squeezed down and after several windings of the string around the casing, the casing will be drawn in to the form shown in Figure 6.

During the wrapping of the string to reach the position shown in Figure 6, the string is carried by clamps 17 and 18 over the top of the casing (toward the left in Figures 3 to 8), down the back side, and toward the forward side (i. e., toward the right hand side in each of Figures 3 through 8). As it passes under the casing, the string tensioned between the casing and clamps 17 and 18, engages the cam surface 32. The cam surface lifts the string sidewise slightly and around the end of the shearing edge 30 and when the string starts up the forward side of the casing, the string is, thus, laid over the shearing edge.

After carrying the string over this surface, the ring continues upwardly across the forward side of the casing and toward the top of the casing, the string being at first loosely looped around the cam surface 32 and shearing edge 30, but as the loop is tightened the slope of the cam surface 32 and the shearing edge 30 is such that the string will easily slip off both of these surfaces so that it can be drawn on around the casing as the clamps carry the string over the top of the casing. The cam surface and the shearing edge are so inclined with respect to the plane of the path of movement of the string that,

when the string looped over the two surfaces is drawn taut, it is caused to slide off of the two surfaces.

When the string has been wound around the casing several times, as shown in Figure 6, the free end of the string may be released from under clamps 17 and 18 and the string will then remain in its wrapped position around the casing because of its frictional engagement with the casing. Thereafter, during the continued movement of clamps 17 and 18 around with the ring to the initial starting position of the ring, they are projected so that they will engage the string at a point between the casing and the guide 42. In Figure 7, the clamp 17 is shown projected so as to engage the string which is held taut between the casing and guide 42 by the string supply means including hold-down arm 41 which is still held in its upper position. As the clamp 17 engages the string, this clamping means is returned to its clamping position and the relation, between the movement of the clamp 17 with ring 15 toward the forward side of the casing, and the hold-down means 41 in returning to its lowered position, is such that the string is held generally taut. The knife hook 47 in driving the string forwardly from the position shown in Figure 7 to the position shown in Figure 8, causes the string to be first engaged under hook 48 and then to engage the cam surface to be lifted around the end of the shearing edge 30, and as soon as the taut string is cammed over the end of the shearing edge it snaps into position on the shearing edge 30.

Upon the ring having been driven to the position shown in Figure 8, it is stopped and the knife blade is reciprocated inwardly whereby the string is severed between the shearing edge 30 and the knife-edge 34.

After the string has been severed, the wrapped string, which has been severed from the supply, remains wound around the casing. The ring, by means of clamps 17 and 18, holds the free end of the string as it falls from the shearing edge. At this stage of the cycle, the ring 15 is held stationary and the conveyors 11 and 14 are energized to carry the casing forwardly to position another, unlinked, portion of the stuffed casing to the tying stations, whereupon, the cycle may be repeated. The ring in beginning a cycle moves from the position shown in Figure 8, upwardly through the position of Figure 2 and on to Figure 3.

It is to be understood that a knife 19 and its cooperating anvil 29 are disposed at each of the tying stations 12 and 13. A machine having a single tying station could be constructed or one having more than two stations. In each case, an anvil and knife in accordance with this invention, will be adapted to each tying station.

It has been found in operating the Demarest et al., machine with the present invention adapted to it, that the cutting action of the machine on the string is greatly improved because of the provision of positive shearing means and because of the use of a self-sharpening of the knife arrangement. The string is positively severed during each cycle of operations and whether it is drawn more or less tightly across the shearing edge, a complete severance is always accomplished. Further, no alteration in the prior art machine is required other than the mounting of an anvil adjacent each of the tying stations and the reshaping of the cutting edge of the knife to adapt it for cooperation with the anvil. The se-

quence of the tying and severing cycle need not be altered in any respect.

The above shows the preferred exemplification of this invention, however, many modifications will occur to those skilled in the art. In its simplest form the anvil 29 includes a cam surface 32 and the nosepiece 33 integral therewith. It is obvious that these pieces may be separately mounted in the machine in a manner to cooperate with the string and knife respectively and with each other, and that driven carrying means to lift the string around the end of the fixed shearing surface could be substituted for the cam surface 32. Such obvious modifications as these and substitutions of equivalents, are all considered to be within the scope of the following claims.

I claim:

1. A string cutting means for a machine for linking a stuffed casing with string delivered from a supply means and having means for carrying a string around a casing and drawing it tight, said means for carrying the string including clamping means for engaging the string to hold the free end while the string is being wrapped around the casing, said clamping means being operative to then release the free end and engage the string at a point between the supply and the casing, comprising an anvil having a shearing edge projecting across the path the string follows in being wrapped around the casing, a cam having a surface to direct the string around the end of the shearing edge during the wrapping step, said shearing edge being positioned to engage the string at a point intermediate the casing and the clamping means when wrapping of the string around the casing is complete, a movable means having thereon a second shearing edge for cooperating with said first named edge to effect severance of the string, and means to drive said movable means over the anvil to drive said second edge against the first named edge after wrapping of the string around the casing has been completed.

2. A string cutting means for a machine for linking a stuffed casing with string delivered from a supply means and having means for carrying the string around a casing and drawing it tight; said means for carrying the string including clamping means for engaging the string to hold the free end while the string is being wrapped around the casing; said clamping means being operative to then release the free end and engage the string at a point between the supply and the casing; comprising an anvil having a shearing edge projecting across the path the string follows in being wrapped around the casing; a cam having a surface to direct the string around one end of the shearing edge during the wrapping step; a nose projecting forwardly from the shearing edge to prevent the string, when slack, from falling off the other end of the shearing edge during the wrapping of the string around the casing; said shearing edge being positioned to engage the string at a point intermediate the casing and the clamping means when wrapping of the string around the casing is complete; a movable means having thereon a second shearing edge for cooperating with said first named edge to effect severance of the string, and means to drive said movable means over the anvil to drive said second edge against the first named edge after wrapping of the string around the casing has been completed.

3. A string cutting means for a machine for linking a stuffed casing with string delivered from

a supply means and having a driven ring means for carrying a string around a casing and drawing it tight, means for driving said ring, said casing being disposed concentrically within the ring during the wrapping step, said ring means including clamping means for engaging the string to hold the free end while the string is being wrapped around the casing, said clamping means being operative to then release the free end and engage the string at a point between the supply and the casing, comprising an anvil having a shearing edge disposed within the ring between the casing and the inner surface of the ring, said edge projecting across the path the string follows in being wrapped around the casing, a cam having a surface to direct the string around the end of the shearing edge during the wrapping step, said shearing edge being positioned to engage the string at a point intermediate the casing and the clamping means when wrapping of the string around the casing is complete, a movable means having thereon a second shearing edge for cooperating with said first named edge to effect severance of the string, and means to drive said movable means over the anvil to drive said second edge against the first named edge after wrapping of the string around the casing has been completed.

4. A string-cutting means for a machine for linking a stuffed casing with string delivered from a supply means and having a driven ring means for carrying a string around a casing and drawing it tight; means for driving said ring; said casing being disposed concentrically within the ring during the wrapping step; said ring means including clamping means for engaging the string to hold the free end while the string is being wrapped around the casing; said clamping means being operative to then release the free end and engage the string at a point between the supply and the casing; comprising an anvil having a shearing edge disposed within the ring between the casing and the inner surface of the ring; said edge projecting across the path the string follows in being wrapped around the casing; a cam having a surface to direct the string around one end of the shearing edge during the wrapping step; a nose projecting forwardly from the shearing edge to prevent the string, when slack, from falling off the other end of the shearing edge during the wrapping of the string around the casing; said shearing edge being positioned to engage the string at a point intermediate the casing and the clamping means when wrapping of the string around the casing is complete, a movable means having thereon a second shearing edge for cooperating with said first named edge to effect severance of the string, and means to drive said movable means over the anvil to drive said second edge against the first named edge after wrapping of the string around the casing has been completed.

5. A string cutting means for a machine for linking a stuffed casing with string delivered from a supply means and having means for passing string around a casing a plurality of times while drawing it tight at each pass, said means for carrying the string including clamping means for engaging the string to hold the free end while the string is being wrapped around the casing, said clamping means being operative to release the free end of the string after wrapping has been completed and then engage the string at a point between the supply and the casing, comprising an anvil having a shearing edge project-

ing across the path the string follows in being wrapped around the casing, a cam having a surface to direct the string around the end of the shearing edge at each pass of the string around the casing during the wrapping step, said shearing edge being disposed at an angle with respect to the plane of the path of the string such that the string may be easily drawn off of the shearing edge at each pass of the string around the casing, said shearing edge being positioned to engage the string at a point intermediate the casing and the clamping means when wrapping of the string around the casing is complete, a movable means having thereon a second shearing edge for cooperating with said first named edge to effect severance of the string, and means to drive said movable means over the anvil to drive said second edge against the first named edge after wrapping of the string around the casing has been completed.

6. A string cutting means for a machine for linking a stuffed casing with string delivered from a supply means and having a driven ring means for passing a string around a casing a plurality of times while drawing it tight at each pass, means for driving said ring, said casing being disposed concentrically within the ring during the wrapping step, said ring means including clamping means for engaging the string to hold the free end while the string is being wrapped around the casing, said clamping means being operative to release the free end of the string after wrapping has been completed and then engage the string at a point between the supply and the casing, comprising an anvil having a shearing edge disposed within the ring between the casing and the inner surface of the ring, said edge projecting across the path the string follows in being wrapped around the casing, a cam having a surface to direct the string around the end of the shearing edge at each pass of the string around the casing during the wrapping step, said shearing edge being disposed at an angle with respect to the plane of the path of the string such that the string may be easily drawn off of the shearing edge at each pass of the string around the casing, said shearing edge being positioned to engage the string at a point intermediate the casing and the clamping means when wrapping of the string around the casing is complete, a movable means having thereon a second shearing edge for cooperating with said first named edge to effect severance of the string, and means to drive said movable means over the anvil to drive said second edge against the first named edge after wrapping of the string around the casing has been completed.

7. A string cutting means for a machine for linking a stuffed casing with string delivered from a supply means and having a driven ring means for passing a string around a casing a plurality of times while drawing it tight at each pass, means for driving said ring, said casing being disposed concentrically within the ring during the wrapping step, said ring means including clamping means for engaging the string to hold the free end while the string is being wrapped around the casing, said clamping means being operative to then release the free end of the string after wrapping has been completed and then engage the string at a point between the supply and the casing, comprising an anvil having a shearing edge disposed within the ring between the casing and the inner surface of the ring, said edge projecting across the path the

string follows in being wrapped around the casing, a cam having a surface to direct the string around one end of the shearing edge at each pass of the string around the casing during the wrapping step, said shearing edge being disposed at an angle with respect to the plane of the path of the string such that the string may be easily drawn off of the shearing edge at each pass of the string around the casing, a nose projecting forwardly from the shearing edge to prevent the string, when slack, from falling off the other end of the shearing edge during the wrapping of the string around the casing, said shearing edge being positioned to engage the string at a point intermediate the casing and the clamping means when wrapping of the string around the casing is complete, a movable means having thereon a second shearing edge for cooperating with said first named edge to effect severance of the string, and means to drive said movable means over the anvil to drive said second edge against the first named edge after wrapping of the string around the casing has been completed.

8. A string cutting means for a machine for linking a stuffed casing with string delivered from a supply means and having a driven ring means for passing a string around a casing a plurality of times while drawing it tight at each pass, means for driving said ring, said casing being disposed concentrically within the ring during the wrapping step, said ring means including clamping means for engaging the string to hold the free end while the string is being wrapped around the casing, said clamping means being operative to release the free end of the string after wrapping has been completed and then engage the string at a point between the supply and the casing, comprising an anvil disposed within the ring between the casing and the inner surface of the ring, said anvil having a shearing edge formed thereon which projects across the path the string follows in being wrapped around the casing, said anvil also having a cam surface formed thereon to direct the string around the end of the shearing edge at each pass of the string around the casing during the wrapping step, said shearing edge being disposed at an angle with respect to the plane of the path of the string such that the string may be easily drawn off of the shearing edge at each pass of the string around the casing, said shearing edge being positioned to engage the string at a point intermediate the casing and the clamping means when wrapping of the string around the casing is complete, a movable means having thereon a second shearing edge for cooperating with said first named edge to effect severance of the string, and means to drive said movable means over the anvil to drive said second edge against the first named edge after wrapping of the string around the casing has been completed.

9. A string cutting means for a machine for linking a stuffed casing with string delivered from a supply means and having a driven ring means for passing a string around a casing a plurality of times while drawing it tight at each pass, means for driving said ring, said casing being disposed concentrically within the ring during the wrapping step, said ring means including clamping means for engaging the string to hold the free end while the string is being wrapped around the casing, said clamping means being operative to release the free end of the string after wrapping has been completed and

then engage the string at a point between the supply and the casing, comprising an anvil disposed within the ring between the casing and the inner surface of the ring, said anvil having a shearing edge formed thereon which projects across the path the string follows in being wrapped around the casing, said anvil also having a cam surface formed on one side thereof to direct the string around the end of the shearing edge at each pass of the string around the casing during the wrapping step, said shearing edge being disposed at an angle with respect to the plane of the path of the string such that the string may be easily drawn off of the shearing edge at each pass of the string around the casing, said anvil including a nosepiece integral therewith, said nosepiece extending forwardly from the shearing edge on the side of the anvil opposite to that of the cam surface to prevent the string from falling off of the shearing edge when it is slack, said shearing edge being positioned to engage the string at a point intermediate the casing and the clamping means when wrapping of the string around the casing is complete, a movable means having thereon a second shearing edge for cooperating with said first named edge to effect severance of the string, and means to drive said movable means over the anvil to drive said second edge against the first named edge after wrapping of the string around the casing has been completed.

10. A string cutting means for a machine for linking a stuffed casing with string delivered from a supply means and having means for carrying a string around a casing and drawing it tight, said means for carrying the string including clamping means for engaging the string to hold the free end while the string is being wrapped around the casing, said clamping means being operative to then release the free end and engage the string at a point between the supply and the casing, comprising an anvil having a shearing edge projecting across the path the string follows in being wrapped around the casing, a cam having a surface to direct the string around one end of the shearing edge during the wrapping step, a nose projecting forwardly from the shearing edge to prevent the string from falling off the other end of the shearing edge when it is slack during the wrapping of the string around the casing, said shearing edge being po-

sitioned to engage the string at a point intermediate the casing and the clamping means when wrapping of the string around the casing is complete, a movable means having thereon a second shearing edge for cooperating with said first named edge to effect severance of the string, said nose being adapted to engage said movable means adjacent its shearing edge to guide it over the other shearing edge, and means to drive said movable means over the anvil to drive said second edge against the first named edge after wrapping of the string around the casing has been completed.

11. A string cutting means for a machine for linking a stuffed casing with string delivered from a supply means and having means for carrying a string around a casing and drawing it tight, said means for carrying the string including clamping means for engaging the string to hold the free end while the string is being wrapped around the casing, said clamping means being operative to then release the free end and engage the string at a point between the supply and the casing, comprising an anvil having a shearing edge projecting across the path the string follows in being wrapped around the casing, a cam having a surface to direct the string around one end of the shearing edge during the wrapping step, a nose extending forwardly from said shearing edge and fixed thereto to prevent the string from falling off the other side of said edge when the string is slack during the wrapping of the string around the casing, said shearing edge being positioned to engage the string at a point intermediate the casing and the clamping means when wrapping of the string around the casing is complete, a movable means having thereon a second shearing edge for cooperating with said first named edge to effect severance of the string, said second shearing edge being disposed at an angle with respect to said first shearing edge so that the movable shearing edge will progressively cross the fixed edge from one side toward the other side whereby the string disposed on the fixed edge will tend to be driven laterally across said first edge toward the base of the nose element whereby the string will be held on said first edge by the movable edge until it is severed by the movable edge.

JAMES J. PROHASKA.
